PLASTIC SHEET MATERIAL

John R. Ellefson, Newburgh, N.Y., assignor to E. I. du Pont de Nemours and Company, Wilmington, Del., a corporation of Delaware

Filed Mar. 14, 1958, Ser. No. 50,031

Term of patent 14 years

(Cl. D87—3)

Fig. 1

Fig. 2

Figure 1 is a plan view of a plastic sheet material showing my new design.

Figure 2 is a cross sectional view taken on line 2—2 of Figure 1.

My design is characterized by a series of spaced apart relatively narrow smooth ribs having wide beveled sides separated by a matte or grained surface, the ribs being slightly raised above the background material but presenting a highly raised effect due to the dull effect of the matte background in contrast with the shiny ribs, all as shown.

I claim:

The ornamental design for plastic sheet material, substantially as shown and described.
